UNITED STATES PATENT OFFICE.

HAKON K. HAUBERG, OF HENNING, MINNESOTA.

WOOD-SPLITTING MACHINE.

1,231,525.

Specification of Letters Patent. Patented June 26, 1917.

Application filed June 20, 1916. Serial No. 104,751.

To all whom it may concern:

Be it known that I, HAKON K. HAUBERG, a citizen of the United States, residing at Henning, in the county of Ottertail and

5 State of Minnesota, have invented new and useful Improvements in Wood-Splitting Machines, of which the following is a specification.

This invention relates to a machine for 10 splitting wood, and particularly to a machine for splitting the sawed blocks of wood into kindling or portions suitable for stove use.

The object of the invention is to provide 15 a wood splitting machine which is simple, strong and durable of construction, reliable and efficient in operation, adapted for splitting a large amount of wood within a given time, and capable of being manufactured and sold at a comparatively low cost.

20 The invention consists of the features of construction, combination and arrangement of parts hereinafter fully described and claimed, reference being had to the accompanying drawings in which:—

25 Figure 1 is a top plan view of a simple form of wood splitting machine embodying my invention, in which but a single splitting tool is used;

Fig. 2 is a side elevation of the same;

30 Fig. 3 is a vertical transverse section on the line 3—3 of Fig. 2;

Fig. 4 is a vertical longitudinal section on the line 4—4 of Fig. 1;

Fig. 5 is a plan view of a portion of the 35 machine frame;

Fig. 6 is a perspective view of the head block;

Fig. 7 is a top plan view of a modified 40 construction of machine of the double cutter type.

Referring to Figs. 1 to 6, inclusive, of the drawings, 1 designates a frame of the wood splitting machine, comprising base sills or runners 2, connected at their ends by cross 45 pieces 3, uprights 4 rising from said sills or runners, a work bench or table 5, supported by the uprights, and a suitable bed or platform 6 mounted upon the rear ends of the sills or runners and forming a support for

50 a motor 7, preferably of the gasolene or other internal combustion type. The apparatus may be designed for use as a permanent fixture, in which case it may be bolted or otherwise secured to a floor or foundation, or it may be of a transportable type, in 55 which event suitable draft appliances may

be employed for drawing it from place to place upon trucks or supporting wheels or upon the sills or runners 2 as sliding surfaces.

The front and rear portions of the table 5 are bifurcated to form receiving slots 8 and 9, and the intermediate portion of the table is also provided with a longitudinal guide opening 10 communicating with the slot 9. 60

The front slot 8 is designed to receive a reduced base portion 11 of a head block 12, which rests upon the upper surface of the table, said block serving as a fixed abutment or support for the wood which is to be 65 split and, if made of wood, being provided, if desired, with a metallic reinforcing and wear surface 13. The block is adjustably mounted in position in order to dispose it in proper relation with respect to the cutting 70 tool to act as a backing for pieces of wood of different lengths which are to be split or subdivided. Pins 14 project from the under- 75 side of the block and are adapted for engagement with spaced series of openings 15, 16 and 17 for adjustably fastening the block in position. A cleat 18 is secured to the underside of the rear part of the base portion 11 of the block and engages under the

table at the opposite sides of the slot 8, thus 80 holding the block from upward displacement, while permitting it to be tilted to a sufficient degree to effect the insertion and removal of the pins within and from the sockets 15, 16 and 17, so that the block may 85 be conveniently adjusted, locked and released as occasion requires in the use of the device. A cross piece 19 extends across the outer side of the slot 8 and limits the outward movement of the block 12, thus preventing its accidental outward displacement, a cross piece 19' connects and reinforces the 90 portions of the table at opposite sides of the opening 9.

The cutter comprises a wedge-shaped 100 splitting knife 20 which is mounted upon the forward end of a bar 21 connected at its rear end with a horizontal transverse crank shaft 22, whereby in the revolution of said shaft the cutter will be reciprocated toward 105 and from the block once on each revolution of the shaft. The shaft is provided with fly wheels 23 and is driven by a chain or other gearing 24 from the motor 7. A swinging arm 25 is pivoted at its lower end to the sills 2 and at its upper end to the cutter, the said 110 upper end of said swinging arm moving in

the slot 10 and thus serving as a guide to cause the cutter, as it is reciprocated, to move in a direct line.

In the operation of the device, the piece 5 of wood, to be split is placed in position upon the table between the cutter and the head block, which has been previously adjusted according to the length of wood to be cut, and the cutting or splitting tool is then 10 set into operation and on its forward motion cuts into and splits the wood in an obvious manner. In the continuous operation of the machine, when splitting a large amount of wood, the split portions of wood may be removed and a new section of wood to be split inserted in place thereon during the period or interval elapsing between the retraction of the cutter and its next ensuing forward stroke; and, inasmuch as the cutter may be 15 operated with any desired degree of rapidity, it will be understood that a very large amount of wood may be split within a given time.

For the purpose of enabling the operator 20 to conveniently handle the material, a work tray or support in the form of a leaf 26 may be arranged at one side of the machine and provided with fastening brackets 27 to engage loops 28 to detachably secure it in position, while an endless conveyer 29 may be mounted at the other side of the machine for rapidly carrying off the split wood. This conveyer 29 is preferably provided with brackets 30 to engage loops 31 similar to the 25 brackets 27 and loops 28, so that it may be detachably fastened in position, and if desired the construction may be such as to adapt the leaf and conveyer to be interchangeably mounted at opposite sides of the 30 machine for right or left hand use. The conveyer is driven by a shaft 32 connected by beveled gears 33 with the driving shaft 22.

If it should be desired to increase the capacity of the machine a double cutter type 40 of machine may be employed, as shown in Fig. 7. In this form of machine a table is provided with guideways 34 at each side for

the cutters and head blocks, and the cutters are coupled by rods or bars 36 to cranks 37 upon the opposite ends of a drive shaft 38, 50 which is provided with an intermediate balance wheel 39 and is driven from the motor in the manner hereinbefore described. With this construction the trays may be mounted at the forward end of the machine on opposite sides of the center thereof and the conveyer may be arranged in the space between the sets of guide passages 34 and head blocks and driven from the shaft 38 by chain and sprocket gearing 41. The mode of use of 55 this form of the apparatus, which allows operators to work at both sides of the table, will be readily understood from the foregoing description.

I claim:—

A machine of the character described comprising a frame, including horizontal sills, supporting posts rising therefrom, and side bars carried by said posts, a table mounted upon said side bars and having longitudinal 70 slots at each end thereof and a division piece between said slots, a swinging arm pivotally mounted at its lower end upon the sills and extending at its upper end through and movable in one of said slots, a cutter 75 pivotally mounted upon the upper end of said arm, a cross piece secured to the side bars and extending transversely across the other slot, an abutment block slidably mounted at the rear portion of its base upon 80 said cross piece, said side bars being provided with dowel seats and said cross piece having dowel pins to adjustably engage said seats, a cross piece upon the base of the forward end of the block extending beneath said 85 side bars, a transverse shaft journaled upon the table and having a crank portion arranged in line with the first-named slot, a pitman rod connecting said crank with the pivoted cutter, and means for driving the 90 shaft for reciprocating the cutter toward and from the block.

In testimony whereof I affix my signature.
HAKON K. HAUBERG.
